Attest.

UNITED STATES PATENT OFFICE

BEN VALJEAN, OF LANSING, MICHIGAN, ASSIGNOR TO MOTOR WHEEL CORPORATION, OF LANSING, MICHIGAN, A CORPORATION OF MICHIGAN

AUTOMATIC DRAFT CONTROL

Application filed September 19, 1929. Serial No. 393,630.

My invention has to do with the automatic control of a variable draft upon a burner whereby to effect and maintain a substantially uniform supply of air to the burner, notwithstanding repeated and even violent fluctuations in the draft due to high winds, unequal combustions or other causes.

Not specifically does my invention supply a need in connection with fluid fuel burners, oil or gas, but is also adapted to solid fuel burners.

In the accompanying drawing and description the invention is set forth in detail as applied to an oil burner by way of example.

15 In the drawing,

Fig. 1 is a vertical section through the lower portion of an oil burning water heater equipped with my improved draft control;

20 Fig. 2 is a front elevation of the draft control;

Fig. 3 is a vertical section on the line 3—3 of Fig 2; and

Fig. 4 is a similar section through a modification.

25 Referring to Fig. 1 of the drawing, a typical form of water heater is represented having an outer casing 11 and an inner casing 12 and with interposed insulating material 13. The water chamber 14 surrounds a centrally disposed combustion chamber 15, the lower portion of which is in open communication with the neck 16 of an oil burner 17 of the carburetor type such as that set forth in my Patent No. 1,512,869 and described 30 as to operation more particularly in my Patents Nos. 1,280,596 and 1,639,202. The burner 17 is enclosed within a housing 18, the only admission of air thereto in substantial amount being by way of an air chute 19, the entrance 20 to which is controlled by the automatic mechanism forming the subject of the present invention and which will hereafter be described in detail.

35 The burner is supplied with fuel through fuel supply pipes 21 and 22 having interposed therein a front chamber 23 of appropriate construction.

Having reference to Figs. 2 and 3, it will be observed that the entrance to the air chute 40 19 is generally rectangular in shape with an

outwardly projecting overhanging upper wall 24 and an inwardly and upwardly projecting arcuate lower wall 25, with substantially vertical parallel side walls 26.

Hinged in the side walls of the opening 20 upon a horizontal pivot 27 is a blade 28

which preferably comprises two offset portions 28^a and 28^b arranged at oblique angles one to the other, as clearly shown in Fig. 3.

By gravity the blade hangs in the position shown in full lines in said figure, thus leaving space between said blade and the walls of the chute at each side and below. Under the influence of normal draft, the blade will be caused to swing inwardly, as shown in

dotted lines, to a position where the space is closed off between the blade and the side walls 26 of the chute, leaving only space between the lower edge of the blade and the curved bottom wall 25.

55 It will be observed that the curvature of the bottom wall 25 is on a radius about a point outwardly and upwardly beyond the pivot 27, with the result that the arc traversed by the lower edge of the blade is eccentric to the arc of the lower wall 25, and consequently the air space between the lower edge of the blade and the wall 25 progressively decreases as the blade swings inwardly to almost a vanishing point at 29 when

60 blade reaches a stop against wall 24.

70 It will be observed that the curvature of the bottom wall 25 is on a radius about a point outwardly and upwardly beyond the pivot 27, with the result that the arc traversed by the lower edge of the blade is eccentric to the arc of the lower wall 25, and consequently the air space between the lower edge of the blade and the wall 25 progressively decreases as the blade swings inwardly to almost a vanishing point at 29 when

75 blade reaches a stop against wall 24.

76 In operation, where there is no draft upon a cold burner, the blade 28 will hang freely as indicated in full lines in Fig. 3. When a draft is induced by the lighting of a fire within the burner, the pressure of the air upon the blade 28 will cause the same to swing inwardly, gradually cutting off the admission of air as the draft increases until a balanced condition is reached.

80 In normal operation of the burner, this balanced draft stage having been reached, the blade of the damper will remain in a substantially constant position subject only to a slight vibration to compensate for any inequalities of

85 combustion or change in chimney draft due to a high wind. It will be observed that at the outset, the admission of air to the chute is quickly reduced as the damper blade starts

90 to swing inwardly, and as the air passage at

100

the side of the blade is cut off; and that thereafter the variations in the air supply are much less pronounced, gradually increasing as the natural draft decreases and decreasing as the natural draft increases so as to maintain a substantially uniform supply of air to the burner under all conditions.

In Fig. 4 a more simple form of the invention is shown wherein the blade 30 pivoted at 10 31 hangs by gravity within the chute and closely adjacent the side walls 32. Here, as in the former case, the curvature of the bottom wall 33 of the chute is eccentric to the arc 34 traversed by the lower edge of the 15 blade 30. The operation is substantially the same as that previously described save that the ratio of change in the air passage is substantially constant, without the rapid initial change.

20 I claim:

1. The combination with an oil burner and a substantially sealed housing therefor having an air inlet chute of gradually decreasing cross-sectional area, of a draft con-

25 trol device comprising a blade offset to lie in oblique planes and hinged at the upper side of the chute entrance and free to swing into said chute under pressure of the draft, the side walls of the chute cut away over an area 30 including the oblique planes whereby the air inlet area is varied inversely with the draft but in decreasing proportion as the draft increases.

2. The combination with an oil burner and 35 a substantially sealed housing therefor having an air inlet chute with parallel side walls and with a lower wall curved inwardly and upwardly, of a draft control device comprising a blade offset to lie in oblique planes and 40 hinged at the upper side of the chute entrance and free to swing into said chute under pressure of the draft, the arc traversed by the lower edge of the blade being eccentric to that of the curved lower wall, whereby the 45 air inlet area is varied inversely with the draft in irregular decreasing proportion as the draft increases.

3. The combination with an oil burner and a substantially sealed housing therefor 50 having an air inlet chute of gradually decreasing cross sectional area, of a draft control device comprising a blade offset to lie in oblique planes and hinged at the upper side of the chute and free to swing into said 55 chute under pressure of the draft, the side walls of the chute cut away over an area including the oblique planes, whereby the air inlet area is varied inversely with the draft first rapidly but in decreasing proportion as the draft increases.

60 In testimony whereof I have hereunto subscribed my name.

BEN VALJEAN.
